UNITED STATES PATENT OFFICE.

INGOMAR STORDAHL, OF MILES CITY, MONTANA.

MECHANICAL FUEL-FEEDING APPARATUS.

1,144,156.

Specification of Letters Patent. Patented June 22, 1915.

Application filed February 8, 1915, Serial No. 6,949.

To all whom it may concern:

Be it known that I, INGOMAR STORDAHL, a citizen of Norway, residing at Miles City, in the county of Custer and State of Montana, have invented certain new and useful Improvements in Mechanical Fuel-Feeding Apparatus, of which the following is a specification.

The present invention relates to improvements in mechanical fuel feeding devices for automatically delivering to a furnace or heater a supply of fuel at a predetermined time.

In understanding the primary object of my invention it may be mentioned that it is generally customary in operating furnaces or similar heaters to throw onto the fire just prior to retiring a sufficient quantity of coal, and leaving the door of the furnace open, allowing the banked fire to smoulder until morning. Now the disadvantage of this is that one must arise in a cold house and suffer the lack of hot water as well as other inconveniences, due to the fact that the temperature has fallen during the night; to overcome the difficulty it is necessary to arise very early for the purpose of putting coal onto the fire, closing the furnace door and starting up the draft to generate heat quickly, resulting, of course, in a waste of fuel and heat units.

With this in view my purpose has been to provide a suitable feeding apparatus, simple in construction yet capable of efficient service, which comprises a fuel supply receptacle disposed adjacent to the furnace with which coöperates a tripping arrangement controlled by a liquid holding container from which the liquid is allowed to drain until an unbalanced condition is reached, whereupon the fuel receptacle is automatically opened to deliver its contents into the fire pot of the furnace.

A further object of my invention is to provide the fuel receptacle of my apparatus with a door or closure which normally maintains the contents therein but coacts in an operated position with the furnace entrance in such a manner as to constitute a chute for the delivery of the coal.

Another object of this invention lies in the provision of an operative connection intermediate the furnace door and the feeding apparatus, such that upon delivery of the fuel into the said furnace the door is automatically closed.

These and such other objects as may hereinafter appear are attained by the novel construction, combination and arrangement of parts to be hereinafter specifically described and claimed.

Reference will now be had to the accompanying drawings forming a part of this specification, wherein:

Figure 1 is a side elevation in normal un-operated position, of an apparatus forming the embodiment of this invention, the fuel receptacle being broken away and shown in section. Fig. 2 is a similar view, parts being shown in section and illustrating the apparatus in its operated position for delivery of coal to the furnace or heater. Fig. 3 is a similar view showing the apparatus in its final position assumed automatically and arranged for closing of the furnace door.

Specifically describing the invention, the numeral 1 designates a supporting standard adjustably connected to the supporting base 2 by means of a fastening member or set screw 3. At one side of the standard adjacent its upper extremity is located the fuel receptacle 4 of any desired shape and size but capable of holding a predetermined amount of fuel which would constitute at least a single supply for delivery to a furnace, such as represented by the reference character 5 adjacent to which the apparatus is disposed. The receptacle is provided preferably with a cover 6 at its top and secured adjacent to its upper end is an operating cord or cable 7 the other end of which is secured to the furnace door 8 in any desired manner. The receptacle 4 is provided with a movable bottom or closure member 9 hingedly connected at 10 and said bottom, it will be observed is of special form in that it is provided with side members 11 for a purpose to be explained more clearly as this description proceeds. The bottom has hingedly connected to its outer end a chute section 12 and a latch bar 13 is movably secured to the receptacle preferably adjacent its upper end so as to interlock or engage with the outer end of the bottom 9 through the instrumentality of its catch extremity 14.

It will be observed by reference to Fig. 1 that in the normal position of the apparatus the bottom 9 is held in closed position by means of the latch bar 13 which acts to sustain the contents of the receptacle until delivery of such contents to the furnace or

22

heater 5 is desired. To accomplish the automatic delivery of the fuel from this receptacle I employ an automatic tripping arrangement consisting of a tripping bar 15 pivoted at 16 intermediate its length to the upper portion of the standard 1. To one extremity of this bar is pivotally connected a movable section 17 the function of which is dual in that in the normal position of the 5 apparatus the section is adapted to be disposed vertically and to engage beneath the bottom 9 of the receptacle 4, in which position it sustains the tripping bar 15 in normal inoperated position. It will be observed also 10 by reference to Fig. 1 that the member 17 when it is released from its engaging position moves in an arc that permits of engagement of the extremity of said member with the catch 14 of the latch bar 13, such engagement being designed for the purpose of 15 releasing the catch from the bottom of the receptacle and allowing such bottom to release the coal contained by the receptacle. When the bottom of the receptacle is released 20 it falls into the position shown most clearly in Fig. 2, and the bottom 9 constituting in such position a chute in coöperation with the chute section 12, the fuel will pass from the receptacle through the furnace door or entrance into which the chute section 12 drops 25 when released by the latch bar 13. The automatic tripping action of the tripping bar 15 is controlled by means now to be described. Disposed on said bar at its end opposite to the end carrying the releasing member 17 is a receptacle 18 adapted preferably to contain liquid and provided with a drain cock or valve 19 from which the liquid 30 intermittently or progressively passes. I 35 preferably provide the container 18 for purposes of convenience with a sight gage 20 or other predetermined means for enabling a proper amount of liquid to be introduced thereinto.

40

45 It will be noted by reference to the drawing that the standard or support 1 is formed with an upper movable section 1^a pivotally secured at 21, this upper section carrying the receptacle 4 at one side and being held 50 in its vertical position by said receptacle when the latter contains a supply of fuel. To limit the movement of the section 1^a so that it will maintain a vertical position normally I secure a stop member or bar 22 to the 55 lower section of the standard, said bar extending above the lower section so as to form a rest against which the upper section 1^a engages. This arrangement is designed for an automatic operation by which the 60 door of the furnace is closed after the supply of fuel from the receptacle has been delivered to said furnace. The receptacle in carrying out this object is provided with an offstanding arm 23 secured to its upper portion 65 and extending rearwardly of the appa-

ratus, said arm carrying an adjustable weight 24 for counterbalancing the receptacle when it has been emptied.

The operation of the apparatus is now apparent from the foregoing description taken 70 in conjunction with the drawings. A sufficient supply of fuel is introduced into the receptacle 4 which is positioned in its normal position shown in Figs. 1 and 2, the latch bar 13 having been engaged with the bottom 75 9 as disclosed by Fig. 1. In the container 18 a predetermined amount of liquid, such as water, is placed and the release member 17 engaged beneath the bottom of the receptacle as shown, wherein the tripping 80 member 15 is held in horizontal position. Opening the drain 19 for the receptacle 18 the liquid will drop therefrom until the supply is exhausted at which time it is designed that the tripping bar will move on its pivot 85 16 in a manner to release the member 17 for pivotal movement as shown by the arrow in Fig. 1. Such pivotal movement of the member 17 brings its outer end into engagement with the catch 14 of the bar 13 releasing 90 the bottom of the receptacle, whereupon said bottom with its chute section 12 drops into position with the latter extending into the entrance of the furnace. The fuel passes from the receptacle into the fire pot 95 of the heater whereupon the receptacle is overbalanced by the weight member 24 which causes the upper section 1^a carrying the receptacle to move on its pivot 21 into the position shown in Fig. 3. In falling 100 into this position the operative connection 7 intermediate the receptacle and the door actuates the door to close the same, whereupon the furnace is in a condition for generating 105 a goodly supply of heat as desired.

110 It will be obvious that the operation of this apparatus may be desirably controlled by experience and tests, for enabling just the proper amount of liquid to be placed in the receptacle 18 which will exhaust at a predetermined time, such for instance as during the later hours of the night, the exact time being determined by the quantity of liquid which is used.

115 It will be noticed by reference to Fig. 2 that the container 18 is especially designed to coact with the section 1^a of the supporting standard for limiting the downward movement of the receptacle bottom 9. This is 120 advantageous, as will be obvious, to insure the proper delivery of fuel to the furnace.

Changes may readily be made in the details of construction of this apparatus without departing from the spirit of this invention and within the scope of the appended 125 claims.

Having thus described the invention, what is claimed as new is:

1. In a mechanical feeding apparatus for furnaces and the like, the combination of a 130

fuel receptacle, a movable closure member therefor, means for maintaining the closure member inoperative, a support for said receptacle for disposing the same adjacent to the furnace, a tripping member arranged adjacent to the receptacle and coacting with the closure member, and means on said tripping member adapted to predeterminedly release the tripping member to cause disengagement of the holding means for the closure member and delivery of the fuel to the furnace.

2. In a mechanical feeding apparatus for furnaces and the like, the combination of a fuel receptacle, a closure member therefor, means for maintaining the closure member inoperative, a tripping member adjacent to the receptacle and engageable with the closure member, and counterbalance means on said tripping member adapted at a predetermined time to cause the tripping member to release the holding means for the closure member aforesaid.

3. In a mechanical feeding apparatus for furnaces and the like, the combination of a fuel receptacle, a closure member therefor, means for maintaining the closure member inoperative, a tripping member adjacent to the receptacle, means carried by said tripping member adapted to engage the receptacle for holding the tripping member in normal position, and counterbalance means on the tripping member adapted at a predetermined time to cause the tripping member to release the holding means for the closure member aforesaid.

4. In a mechanical feeding apparatus for furnaces and the like, the combination of a fuel receptacle, a movable closure member therefor, holding means for the closure, and means for tripping the holding means to release the contents of the receptacle and for limiting movement of the closure member, said closure member constituting a chute in release position for conveying the fuel into the furnace.

5. In a mechanical feeding apparatus for furnaces and the like, the combination of a fuel receptacle, a closure member pivotally mounted at the bottom of said receptacle, a latch normally holding the closure member in closed position, a trip bar tiltingly mounted adjacent to the receptacle for releasing the latch, and means on said bar for automatically causing tilting action thereof.

6. In a mechanical feeding apparatus for furnaces and the like, the combination of a fuel receptacle, a closure member pivotally mounted at the bottom of said receptacle, a latch normally holding the closure member in closed position, a trip bar pivoted intermediate its ends adjacent to the receptacle, a latch engaging member connected to the bar and adapted to hold the bar in normal position, and trip control means on said bar

for releasing the latch engaging member to permit disengagement of the latch member and movement of the closure.

7. In a mechanical feeding apparatus for furnaces and the like, the combination of a fuel receptacle, a closure member therefor, holding means for the closure member, and a tripping member for tripping the holding means to open the receptacle including control means for controlling the movement of said closure member, said means comprising a liquid holding receptacle adapted to contain a predetermined amount of liquid whereby upon draining of said liquid therefrom to permit movement of the tripping member for releasing the holding means and the closure member.

8. In a mechanical feeding apparatus for furnaces and the like, the combination of a fuel receptacle, a closure member therefor, holding means for the closure member, a tripping member pivoted intermediate its length adjacent to the receptacle and engageable at one end with the closure member to hold the tripping member in normal position, and means controlling movement of the tripping member carried by the other end, said means comprising a liquid holding receptacle from which the liquid is gradually drained whereby to unbalance the tripping member at a predetermined time for releasing the holding means aforesaid.

9. The combination with a furnace having a door, of fuel feeding apparatus therefor disposed adjacent to the furnace and comprising a fuel receptacle, a support therefor on which said receptacle is disposed for movement, connecting means intermediate the furnace door and the receptacle, and discharging means for said receptacle for permitting delivery of its fuel contents to the furnace, said receptacle being automatically movable upon such discharge to actuate the furnace door.

10. The combination with a furnace having a door, of fuel feeding apparatus therefor disposed adjacent to the furnace and comprising a fuel receptacle, a support for said receptacle consisting of a movable section to which said receptacle is attached, counterbalance means arranged to overbalance the receptacle when discharged whereby upon discharge of its contents to move the movable support section into inoperative position, and means intermediate the receptacle and the furnace door for actuating the latter upon movement of said receptacle.

11. The combination with a furnace having a door, of fuel feeding apparatus therefor disposed adjacent to the furnace and comprising a fuel receptacle, a support for said receptacle consisting of a movable section to which said receptacle is attached, counterbalance means arranged to overbalance the receptacle when discharged where-

by upon discharge of its contents to move the movable support section into inoperative position, means intermediate the receptacle and the furnace door for actuating the latter upon movement of said receptacle, and means for limiting movement of the movable section whereby to hold said section in normal operative position.

12. In an apparatus of the class described, the combination with a furnace, of fuel feeding apparatus therefor comprising a receptacle, a standard for said receptacle consisting of a movable section to which the receptacle is connected at one side, a counterbalance member extending from said movable section oppositely with respect to the receptacle, a movable closure member for said receptacle, means for maintaining said closure member in closed position for sustaining the contents of the receptacle, automatic tripping mechanism for causing release of the closure member including control means for controlling tripping action of the tripping member whereby to release the contents of the receptacle for delivery to the furnace at a predetermined time and to move said receptacle into an inoperative position upon discharge of said contents.

13. In an apparatus of the class described,

the combination with a furnace, of fuel feeding apparatus therefor comprising a receptacle, a standard for said receptacle consisting of a movable section to which the receptacle is connected at one side, a counterbalance member extending from said movable section oppositely with respect to the receptacle, a movable closure member for said receptacle, means for maintaining said closure member in closed position for sustaining the contents of the receptacle, 30 automatically tripping mechanism for causing release of the closure member including control means for controlling tripping action of the tripping member whereby to release the contents of the receptacle for delivery to the furnace at a predetermined time, and an operating connection intermediate the receptacle and the furnace door whereby upon discharge of the receptacle 35 contents the receptacle is moved into inoperative position and the door of the furnace is automatically actuated.

In testimony whereof I affix my signature in presence of two witnesses.
